UNITED STATES PATENT OFFICE.

RALPH WALSH, OF WASHINGTON, DISTRICT OF COLUMBIA.

VACCINE-CARRIER AND CASE.

SPECIFICATION forming part of Letters Patent No. 634,709, dated October 10, 1899.

Application filed August 15, 1899. Serial No. 727,336. (No model.)

To all whom it may concern:

Be it known that I, RALPH WALSH, of the city of Washington, in the District of Columbia, have invented a new and useful Improvement 5 in Vaccine-Carriers and Cases Therefor, of which the following is a specification.

My invention has relation to carriers for glycerinized vaccine-lymph and cases therefor, the object being to protect as far as possible 10 the lymph from absorption and from the injurious effects of the atmosphere and in so doing to provide for the loaded or charged point of the carrier a simple and effective case or protecting-shell and one which is adapted 15 for use with individual vaccine-carriers.

In a prior patent, No. 616,042, granted to me December 13, 1898, I have described and claimed a vaccine-carrier case having a protecting case or shell of paraffin or other material 20 which is non-absorbent and non-destructive of glycerinized vaccine-lymph, into which the charged point of the carrier is sealed. My present invention is an improvement upon said patented invention.

Under my present improvement the case or shell for the vaccine-carrier is composed of a strip of paraffin-coated pliable material which is doubled or folded on itself, paraffin face inward, and has between its meeting faces a 25 pocket to receive the vaccine-charged point of the carrier, which is sealed into said pocket, the paraffin coat thus becoming the lining of the shell. Such a case or shell, while it may be used to contain more than one carrier and 30 for that purpose may be provided with more than one pocket, is particularly adapted to be used in connection with a single carrier, and it is for that purpose that it has been more especially designed.

In lieu of paraffin I may use stearin or wax or other suitable material which is non-absorbent and non-destructive of glycerinized vaccine-lymph, and I desire to be understood as including any such modification in my 45 claim.

To enable others skilled in the art to make and use my invention, I will describe by reference to the accompanying drawings the best way now known to me of carrying the same 50 into effect.

In the drawings, Figure 1 is a perspective view, and Fig. 2 is a longitudinal section on

line 22, Fig. 1, of the completed article. Figs. 3 to 6^a, inclusive, are views illustrative of the material and tools employed in and the various stages of the manufacture of the case or shell.

The shell or case is formed from a strip of paper or other pliable material having an adherent coat of paraffin of the proper thickness. I prefer to use for this purpose a large sheet of paper *a*, as indicated in Figs. 3 and 3^a, which is ruled off by lines into subdivisions, each of which is of the size of the strip required. Upon this sheet is poured or spread melted paraffin in quantity to form when it solidifies an adherent coat or layer *b* of the proper thickness. The prepared sheet is then cut up along the lines indicated into separate strips of the desired dimensions. The next step is to double each strip on itself, paraffin face innermost, and to join its meeting faces, except where the pocket is to be formed for subsequent reception of the vaccine-charged point of the carrier. This is conveniently done by placing the strips upon a metal surface or plate heated to such an extent as to properly soften the paraffin and then picking up each strip by a tool *c*, such as shown in Fig. 4, the point *c'* of which is of the shape required for the pocket. The point of the tool is pressed lightly into the softened paraffin coat about midway between the ends of the strip and is then raised, carrying with it the strip, which by hand is doubled upon itself and pressed together around and from opposite sides of the point *c'* of the tool, as seen in Fig. 5. This tool is in effect a former or core, which when thus loaded is placed in a mold *d*, as in Fig. 6, the hinged top of which mold is then brought down upon the folded strip, so as to press its meeting faces closely together and in intimate union around the former or core *c'*. The side edges of the case or shell which, as shown in Fig. 6^a, may protrude beyond the mold are trimmed off, the shell is taken from the mold, and the former *c'* is withdrawn from the shell, leaving it in the condition shown in Fig. 7, with a molded pocket *p* ready to receive the charged point of the ivory-carrier *A*, Figs. 1 and 2. The ivory point after being charged with glycerinized vaccine-lymph is inserted into the pocket in the shell far enough to take hold of

the shell, and the latter, held by carrier A, is then dipped for an instant into melted paraffin far enough to seal the joint between the mouth of the pocket in the shell and the carrier, and 5 the article is then thrown at once into ice-water in order to cool and solidify the paraffin. This completes the article, and in this completed condition it is shown in Figs. 1 and 2, in which figures B is the doubled or folded external 10 strip of paper or pliable material, C is the inner coat of paraffin or equivalent material, A is the ivory-carrier having its vaccine-charged point contained in the pocket formed between the meeting faces of the inner paraffin coat, and s is the seal at the mouth of 15 the pocket, formed by dipping the shell into paraffin, as last above described. This shell is easily, quickly, and cheaply made, is strong and effective for the purpose for which it is 20 designed, and admits of the carrier A being

removed from it readily and without injury to the vaccine charge.

Having described my invention and the manner in which the same is or may be carried into effect, what I claim herein as new, 25 and desire to secure by Letters Patent, is—

A vaccine-carrier case or shell composed of a strip of pliable material coated with paraffin, doubled or folded on itself, paraffin face inside, and having its meeting paraffin faces united 30 except where the pocket is left, into which pocket is sealed the vaccine-charged point of an individual carrier, as hereinbefore set forth.

In testimony whereof I have hereunto set 35 my hand this 11th day of August, 1899.

RALPH WALSH.
